US0D1062636S

(12) **United States Design Patent** (10) **Patent No.:** **US D1,062,636 S**
(45) **Date of Patent:** **** Feb. 18, 2025**

(54) **SOCKET**

(71) Applicant: **Hangzhou Kaite Electrical Appliance Co., Ltd.**, Jiande (CN)

(72) Inventor: **Min Xu**, Jiande (CN)

(73) Assignee: **Hangzhou Kaite Electrical Appliance Co., Ltd.**, Jiande (CN)

(**) Term: **15 Years**

(21) Appl. No.: **29/862,620**

(22) Filed: **Dec. 11, 2022**

(51) LOC (15) Cl. **13-03**

(52) U.S. Cl.

USPC **D13/137.2; D13/137.4**

(58) **Field of Classification Search**

USPC D13/101, 103, 107, 108, 118, 119, 120, D13/123, 133, 137.1, 137.2, 137.3, 137.4, D13/138.1, 138.2, 139.1, 139.2, 139.6, D13/139.7, 139.8, 146, 147, 153, 158, D13/160, 161

CPC H01R 13/04; H01R 13/10; H01R 13/11; H01R 13/46; H01R 13/68; H01R 13/518; H01R 13/642; H01R 13/713; H01R 13/7135; H01R 25/003; H01R 25/006; H02J 50/80

(57) **CLAIM**

The ornamental design for a socket, as shown and described.

DESCRIPTION

FIG. 1 is a front perspective view of a socket, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate the portions of the socket, which form no part of the claimed design.

1 Claim, 7 Drawing Sheets
